CLAIM

The ornamental design for a ceiling fan blade iron, as shown and described.

DESCRIPTION

FIG. 1 is a bottom perspective view of a ceiling fan blade iron shown in the environment of a ceiling fan, showing my new design;

FIG. 2 is a top perspective view of the ceiling fan blade iron, having the ceiling fan environment removed;

FIG. 3 is a right side view thereof;

FIG. 4 is a front side view thereof;

FIG. 5 is a bottom view thereof; and,

FIG. 6 is a top view thereof.

Portions of the ceiling fan blade iron and ceiling fan environment shown in broken lines form no part of the claimed design.
